SHOE SOLE FITTING MACHINE

Ernest W. Stacey, Beverly, Mass., assignor to
 United Shoe Machinery Corporation, Paterson,
 N. J., a corporation of New Jersey

Application September 9, 1935, Serial No. 39,716

14 Claims. (Cl. 12—17)

This invention relates to shoe sole fitting machines and is herein shown and described as embodied in a machine arranged to receive and perform a series of operations upon a sole blank, either a block sole or a slightly oversized blank die cut to approximately the required shape, producing from the blank a sole which is fully prepared for attachment to a shoe by the cement process.

10 Although the operations performed by the illustrated machine include rounding, forepart reducing, shank reducing, roughing and final trimming, the invention is not limited in its application to a machine which will perform all of those 15 operations, but includes within its scope improved mechanisms for performing only a part or parts thereof.

In my prior application Serial No. 727,765, filed May 26, 1934, there is disclosed and broadly 20 claimed a machine which, in its entirety, is adapted to perform the above named operations upon a die cut sole blank, and the present invention may, in some of its aspects, be regarded as a development of and improvement upon the invention 25 which is the subject-matter of the said application.

One object of the present invention is to widen the range of utility of such machines as that above referred to, providing a machine which is capable 30 of operating upon block soles as well as die cut blanks, and is capable of operating all the way around the sole. To this end a slideable and rotatable sole pattern supporting jack is provided with a cooperating clamping member arranged to 35 hold a sole blank upon the pattern while the jack is rotated through a complete revolution, without obstructing any part of the periphery of the sole from the action of the cutter or cutters arranged to operate upon it.

40 As shown, this result is secured by supporting the clamping member separately from the jack and keeping it in register with the pattern by connections, such as gearing or the like, between 45 the clamping member and the jack.

Another feature of the invention consists in the provision of control mechanism operating to cause the cutter to be swung into engagement with the sole before the jack starts to turn and then causing the jack to turn so that the entire periphery of the sole will be operated upon. After the rotation of the jack is complete, the cutter is retracted to an inoperative position where it will not interfere with the removal of the finished 55 blank.

A further feature of the invention resides in the provision of a tilting cutter head carrying a pair of cutters and having means for so biasing the head that the cutters engage the blank in succession when the cutter head is moved toward the 5 blank to be operated upon.

The invention also includes a new construction and arrangement whereby the cutter, which is rotary and turns in a direction to cut toward the rear end of the sole, is caused to engage and cut 10 into the edge of the sole at one side of the heel portion thereof, after which the jack is rotated in the direction opposite to the cutting action, causing the entire periphery of the heel portion 15 of the sole to be traversed past the cutter. This initial engagement of the cutter with the sole as described permits the cutter to cut its way into the sole with a minimum tendency to buckle the sole because the drag of the cutter is not directly 20 toward the clamping member.

The above and other features of the invention and benefits derived therefrom will be better understood and appreciated from the following detailed description of one embodiment thereof taken in connection with the accompanying drawings, in which

Fig. 1 is a front view of the machine with parts broken away to show the internal mechanism;

Fig. 2 is a left hand end view, partly in elevation and partly in section;

Fig. 3 is a view of a detail of the cutter driving mechanism;

Fig. 4 is a plan view of the base portion of the machine;

Fig. 5 is a vertical sectional view of the cutter 35 head;

Fig. 6 is a plan view of the cutter head;

Fig. 7 is a side elevation of the cutter head;

Fig. 8 is a vertical section of the cutter head biasing device;

Fig. 9 shows the power transmission unit in horizontal section;

Fig. 10 is a plan view of the control unit;

Fig. 11 is an elevation of the control unit;

Fig. 12 is an enlarged view of a detail of the 45 clamp operating mechanism;

Figs. 13, 14 and 15 show details of the clamp adjusting mechanism, and

Fig. 16 is an angular view of the clutch and cam elements of the control unit.

Referring now to the drawings, and particularly to Figs. 1, 2 and 4, 20 indicates a machine frame or housing the top of which constitutes a table 22 above which the operating mechanisms of the machine are supported, while various driving and 55

control mechanisms are enclosed within the housing beneath the table.

Power is furnished by a motor 24 connected by a belt 25 to a pulley 28 which is keyed upon a shaft 30 (see Fig. 9) extending into a case 32 which contains mechanism for transmitting power to the cutting tools which operate upon the work.

Referring now particularly to Fig. 9, the shaft 30 is journaled in ball bearings 34, 36 which are supported in the case 32. Keyed to the shaft 30 near its inner end is a spiral gear 38 meshing with a similar spiral gear 40 keyed upon a vertical shaft 42 journaled in bearings 44, 46 (see Fig. 1) which are mounted in a stationary upright sleeve 48 secured in the table 22 by a bolt 50. The shaft 42 serves to transmit power to a pair of rotary tools through further mechanism which will be described in detail hereinafter.

Also meshing with the driven spiral gear 40 is another spiral gear 52 secured upon a horizontal shaft 54 journaled in bearings 56, 58 in the case 32 and arranged parallel to the shaft 30. The shaft 54 which is thus driven by the shaft 42 also carries a spiral pinion 60 which meshes with a spiral gear 62 (see Fig. 1) upon a horizontal shaft 64 extending from front to rear of the case 32 and having at its rear end a pinion 66 which meshes with an internal gear 68. The gear 68 has secured upon its rear face an eccentric 70 and is rotatably mounted upon a fixed stud 72 extending rearwardly from the case 32.

It will be apparent that whenever the motor 24 is running the shaft 42 will be in rotation and will be driving the eccentric 70.

The eccentric 70 is surrounded by an eccentric strap 74 (Figs. 4 and 9) upon one end of a connecting rod 76, the other end of which is pivotally connected at 78 to a reciprocable rack 30 (Fig. 11) which is guided for horizontal movement in a control unit which will be described hereinafter.

The right hand end of the shaft 54, as seen in Fig. 9, projects from the case 32 and is squared as shown at 82 for the reception of a hand crank by which the mechanism of the machine may be turned over manually when desired.

At the upper end of the shaft 42 is secured a skew gear 84 which meshes with a gear 86 secured to an inclined shaft 88 the lower end of which runs in a bearing 90 supported in a hollow arm 92 which is integral with a hollow post 94 mounted to oscillate about a vertical axis and journaled for that purpose upon the upright sleeve 48. The post 94 is flanged at its lower end 96, the flange resting upon the table 22 and being held down to the table by gib 98 (Figs. 1 and 4).

As a result of the construction just described, the upper end of the hollow arm 92 is able to swing through a considerable arc around the axis of the shaft 42. The said upper end of the arm 92 carries a forwardly extending hollow bracket 102 (Figs. 2 and 3) from which is supported a depending cutter head. Journaled upon ball bearings 104, 106 within the bracket 102 are a pair of gears 108, 110 which are rigidly connected together by a sleeve 112. The upper gear 108 meshes with a skew gear 114 secured to the upper end of the inclined shaft 88 and the lower gear 110 meshes with a gear 116 at the upper end of a short shaft 118 arranged to turn about a vertical axis in bearings 120 and carrying at its lower end a pinion 122 (see Figs. 3 and 5). The bearings 120 for the shaft

118 are supported by a retainer 124 engaged in a groove in the depending portion of the bracket and the gear 122 upon the lower end of the shaft is the main driving gear for a pair of rotary tools 126 and 128 which perform rounding, shank reducing and roughing, edge trimming and forepart reducing and roughing operations upon the work.

The tool 126 is mounted upon the lower end of a vertical shaft 130 (see Fig. 5) which is suspended for rotation in a ball bearing 132 carried by a slide 134 (Figs. 5, 6 and 7) guided for limited vertical movement in the cutter head casting 136 and supported by a compression spring 138. The shaft 130 is continuously rotated by a gear 140 which meshes with, and is driven by, the gear 122. The gear 140 is mounted upon, and keyed to, a sleeve 141 which runs in bearings 143. The shaft 130 is slidable vertically through the rotating sleeve but is caused to rotate with the sleeve by splines 145 connecting the shaft and sleeve.

The tool 126 comprises toothed shank reducing and roughing blades 142 and a rounding cutter 144 which operate upon the sole blank in the same manner as the corresponding elements in the machine disclosed in my prior application. The vertical movement of the tool 126 to throw the reducing and roughing blades 142 into or out of operation while permitting the rounding cutter 144 to continue to operate upon the sole edge is effected by a bell crank lever of which the horizontal arm 146 engages in a notch in the slide 134 and the vertical arm 148 is operated around the pivot 150 by a slide carrying a guide roll which engages and is controlled by the pattern or templet upon which the sole blank is clamped, substantially as in my said prior application. For the purpose of adjusting the throw of the bell crank lever arm 146 the arm 148 is made in two parts connected together by an adjusting screw 152 provided with a convenient knob 154 the hub of which is engaged by a detent 156.

The lower end of the lever arm 148 engages the rear end of a slide 158 which carries at its front end the guide roll 160 arranged to engage the sole pattern and be actuated thereby. Beneath the roll 160 is a gage 161 carried by an adjustable slide 163 arranged to be secured in adjusted position by a set screw 165. This gage, contacting with the edge of the pattern 272, determines the line to which the cutter 144 shall round the sole blank.

Also meshing with the driving gear 122 is a second driven gear 162 which is keyed to a sleeve 164 running in bearings 166. Slidable vertically through this sleeve is a shaft 168 constrained by splines 170 to rotate with the sleeve and carrying at its lower end the sole edge trimming cutter 172. The forepart reducing and roughing blades 174 of the tool 128 are carried by the sleeve 164 whose bearings 166 are mounted in a vertically adjustable slide 176, while the edge trimming cutter shaft 168 is supported by a bearing 178 which is mounted in a vertically adjustable slide 180.

Clamped between the slide 176 and a plate 182 secured thereto is a lug 184 which projects laterally from a slide 186 urged upward by a spring 188. Arising from the plate 182 is a screw 190 upon which is threaded a nut 192 whose lower end is flanged and restrained from vertical movement by a cover plate 194 secured to the top of the casing 136. By rotating the nut 192 the

slide 176, and consequently the cutter blades 174 may be adjusted up or down.

Similarly, vertical adjustment of the shaft 168 and the cutter 172 is effected by a nut 195 threaded upon a screw 198 arising from the slide 180, and either adjustment may be changed independently of the other. The face of the slide 186 is visible through a window opening 200 in the wall of the casing 136 and may be graduated to indicate cutter settings for sole blanks of different thicknesses.

Mounted upon an adjustable slide 167 secured in position by a set screw 169 beneath the cutters 172 and 174 is a guide roll having a portion 171 arranged to run against the edge of the pattern to determine the depth of cut of the edge trimming cutter 172, and a portion 173 of larger diameter which runs in a groove around the forepart and heel portions of the pattern but in the shank portion, where there is no groove in the edge of the pattern, causes the cutter head to be tilted just sufficiently to render this cutter inoperative upon the shank portion of the sole blank.

The swinging of the post 94 and the cutter head carrying arm 92 in a counterclockwise direction in order to advance the cutter toward the work is accomplished by a large compression spring 222, Fig. 4, surrounding a guide rod 224, one end of which is pivoted to an arm 226 affixed to a vertical rock shaft 228. The other end of the rod and spring enter a bushing 230 which is threaded through the machine housing 20 and provided with an external knob 232 for turning the bushing to adjust the tension upon the spring.

To the upper end of the rock shaft 228 is affixed a rocker arm 234 connected by a link 236 to an arm 238 projecting from the rear side of the post 94. With the connections as described, the expansive force of the spring 222 tends to swing the post and the cutter head arm carried thereby in a direction to move the cutter head toward the work and does so unless the arm carrying the cutter head is forcibly retracted against the expansive effort of the spring.

The sole blank to be operated upon, designated in Figs. 1 and 2 by the numeral 240, is clamped in a jack and rotated past the tools in substantially the same manner as in the machine of my prior application except that in the present machine the blank is placed on top of the wooden supporting pattern and faces upward instead of being placed against the under side of the pattern and facing downward, as in the earlier machine.

Power for rotating the jack is derived from a pulley 242, integral with the pulley 28 which is belted to the motor. The pulley 242 is belted to a pulley 244 (Figs. 1 and 4) which is loose upon a worm shaft 246 carrying a worm 248, but is capable of being placed in driving connection with said shaft by means of a clutch 250 capable of being shifted axially of the shaft and having at one side a friction facing 252 for engaging the pulley 244 and at the other side a friction facing 254 for alternatively engaging a stationary disk 256 to act as a brake to stop rotation of the worm shaft.

The worm 248 meshes with a worm gear 258 (Fig. 2) which is keyed to a shaft 260 having at its rear end a bevel pinion 262 meshing with a bevel gear 264 affixed to the lower end of a vertical shaft 266 which passes upward through the table 22 and carries at its upper end a gear 268 for driving the internal elliptical rack 269 by which the jack is rotated in substantially

the same manner as in the machine of my previous application.

The sole blank to be operated upon is placed upon a wooden pattern 272 having its edge grooved around the forepart as shown at 273 and around the heel end as shown at 275. The pattern rests upon two supporting posts 274 carried by a rotary jack table 276 to the under side of which is attached a gear 278. Meshing with the gear 278 is an idle gear 280 which in turn meshes with a gear 282 affixed to the lower end of a vertical shaft 284 journaled in bearings in a hollow upright clamp support 286 which is part of a C-shaped casting in the base portion 287 of which the jack table 276 may rotate. The upper, overhanging, portion of this casting carries the work clamping mechanism and the support 286 is entirely outside of the jack and is movable relatively thereto. At the upper end of the shaft 284 is secured a gear 288 which is connected through a series of idle gears 290 to a gear 294 through which passes a clamp supporting shaft 296. The shaft 296 is constrained to rotate with the gear 294 but is freely slidable vertically through said gear and is provided at 298 with a thrust bearing to receive the downward thrust of the arm 300 of a lever pivoted at 302 to the jack head and having its other arm 304 urged upward by a compression spring 306 the lower end of which is supported by a bracket 308 projecting from the upright member 286 of the jack casting. A collar 310 secured to the upper portion of the shaft 296 and resting on top of the lever arm 300 serves to elevate the shaft when the spring 306 is compressed and the lever is rocked.

The construction just described permits the work to be rotated through a complete revolution with the periphery of the pattern 272 unobstructed and, consequently, enables the cutters to operate all the way around the sole blank, including the heel end. This was impossible with the machine of my prior application, in which a cam at the heel end of the pattern was employed to guide the cutters into the sole blank at one side of the heel portion and out of it at the other side so that the heel end of the blank could not be operated upon.

The lower end of the shaft 296 carries a horizontal cross-head 312 (Figs. 13, 14 and 15) upon which are mounted slides 314 and 316 carrying respectively the forepart and heel clamping posts 318 and 320. The slides 314 and 316 are arranged for adjustment toward or from each other to accommodate work of different lengths by a right and left screw 322, 324 threaded through nuts 326 and 328 upon the respective slides and having its central portion journaled in a bearing 330 to prevent endwise movement of the screw.

At the center of the screw is a spiral gear 332 which meshes with a gear 334 carried by shaft 336 which also bears a knob 338 by which the adjustment may be performed.

Each of the posts 318, 320 depends from a plate 340 supported on the underside of the slide 314 or 316. The plate 340 is capable of swinging about a pivot pin 342 into either of two angular positions determined by notches 344 one or the other of which is engaged by a spring-pressed detent 346. This permits the work clamping posts to be swung at will into position to accommodate and clamp either right or left soles.

Normally the spring 306 acts to force down the clamping posts 318 and 320 to hold the sole blank 240 clamped firmly upon the pattern 272.

during the operation of the machine upon the blank. When it is desired to release the sole and insert another blank the clamping members are raised by depressing a treadle 350 which, through 5 connections now to be described, causes the spring 366 to be compressed and the clamping posts 318, 320 to be raised.

- The arm 304 is pivotally connected at 352 to a rod 354 which passes downward through the 10 spring 366 and the bracket 306, terminating in a member 356 which is guided for vertical sliding movement by a bolt 360 passing through a slot in it. The lower end of the member 356 is bent at right angles to form a horizontal hook 362. 15 Arranged to overlie and engage the top face of the hook 362 is an elongated plate 364 (Figs. 1, 4 and 12) which is affixed to the top of a plunger 366 guided for vertical sliding movement through the table 22.
- 20 The lower end of the plunger 366 is connected by a link 368 to a lever 370 movable about a stationary pivot 372. This lever has a projecting tail portion 374 upon which bears a spring-pressed plunger 376 which tends to raise the 25 plunger 366.

Mounted in the lever 270 are two horizontal pins 378 and 380 adapted to be engaged alternatively by a double hook 382 secured to the upper end of a rod 384, the lower end of which is pivot- 30 ed to the treadle 350 at 386. The treadle rod 384 is surrounded by a compression spring 388 which tends to elevate it and the hook 382.

From the foregoing it will be apparent that when the treadle is depressed the hook 382, engaging one or the other of the pins 378, 380 will draw down the plunger 366 which, in turn, will pull down the rod 354 and cause the sole clamping members 318, 320 to be raised.

Ordinarily the clamp need be opened only a 40 short distance to permit a sole to be removed and a new blank to be inserted but when it is desired to change patterns it is necessary to lift the clamping posts higher and this is accomplished by swinging the hook member 382 to the right, as 45 viewed in Fig. 12, so that it will engage the pin 380 instead of the pin 378. This is accomplished manually by pulling outward upon a knob 390 which is connected by a rod 392 to the double hook member 382. The rod 392 is surrounded 50 by a compression spring 394 which normally keeps the hook 382 at the left, as seen in Fig. 12, so that it will engage the pin 378. Since the pin 380 is only about half as far from the fulcrum pivot 372 as is the pin 378, it will be obvious that 55 with a given amount of depression of the treadle the clamp will be opened twice as far if the hook 382 engages the pin 380 as it will if the hook engages the pin 378.

The various operating mechanisms already de- 60 scribed are controlled and coordinated by a control unit which is best illustrated in Figs. 4, 10, 11 and 16.

Meshing with the rack 80 which, as previously stated, reciprocates continually when the motor 24 is running, is a pinion 396 to which is affixed a disk 398, the gear and disk constituting a unit which is mounted to rotate loosely upon a vertical shaft 400 journalized in bearings 402, 404 formed in a controller housing 406 which is located in the left rear corner of the machine, as 65 seen in Fig. 4, beneath the table 22. By reason of the permanent engagement of the gear 396 with the rack 80 the disk 398 is kept in continual 70 oscillation.

75 Referring to Fig. 16, a pawl 408 is inserted in

the top of the disk 398, being normally pressed upward above the surface of the disk by a spring 410. Loosely disposed upon the shaft 400 above the disk 398 is another disk 412 having a downwardly projecting tooth 414 arranged to be engaged by the end of the pawl 408. The rear faces of both the pawl 408 and the tooth 414 are beveled off so that the disk assembly just described constitutes in effect a positive one-way clutch. 5

In order to provide for engagement and disengagement of the clutch the disk 412 is slidable vertically upon the shaft 400 and its hub is provided with notches 416 in which are permanently engaged tongues 418 which extend downward from a cam disk 420 fixedly secured to the shaft 15 400 by a pin 422. As a result of this construction it is possible to raise and lower the disk 412 relatively to the shaft 400 but it is impossible for the said disk to turn relatively to the shaft. 10

For the purpose of raising and lowering the 20 disk 412, thereby disengaging and engaging the clutch, the disk is provided with a peripheral groove 424 in which lie the fingers 426 of a horizontal clutch shifting lever 428 which is movable about a stationary pivot 430 and has rigid with 25 it an upright arm 432, connected by a pull spring 433 to the controller box, through which arm the clutch shifting lever is actuated. The lever 428 is forked, as is usual in devices of this kind, and a locking pawl 434 acting under the 30 influence of a spring 436 is arranged to engage its rear arm and hold it down, with the tooth 416 in a position to be engaged by the pawl 408 and the toe end of the locking pawl in a position to be engaged by a striker 437 which extends 35 upward from the disk 398, see Figs. 10, 11 and 16.

Passing through a hole in the upper end of the arm 432 is a rod 438 surrounded at both sides of the clutch shifter arm by compression springs 440, 442 which are retained respectively 40 by collars 444, 446 secured to the rod 438 by set screws.

The right hand end of the rod 438 is pivotally connected at 448 to the rear end of a lever 450 which is utilized to shift the clutch 250, said 45 lever being movable about a fixed pivot 452. From a brief examination of Figs. 4, 11 and 16 it will be seen that when the clutch 398, 412 is in a position for engagement the clutch 250 will be disengaged and vice versa. 50

A cam 454 is secured to the cam disk 420 by a bolt 456 passing through an arcuate slot 458 in the disk, rotary adjustment of the cam relatively to the disk and to the shaft 400 to which the disk is pinned being permitted when the nut 55 460 upon the bolt 456 is loosened.

The disk 420 has a notch 462 adapted to be engaged by the point of a locking dog 464 movable about a stationary pivot 466 and having a tail portion 468 disposed for engagement by another dog 470 which is secured to a vertical rock shaft 472 journalized in a stationary upright bearing 474. A spring pressed plunger 476 bearing upon a lug 478 integral with the dog 464 tends to swing the dog into the notch 462. 60

Secured to the lower end of the rock shaft 472 is an arm 480 which carries a roll 482 engageable in a recess 484 in the edge of the disk 398. It is only when the disk 398 is in a position to permit the roll 482 to enter the recess 484 that 70 the dog 470 can be swung counterclockwise, as seen in Fig. 10, to retract the dog 464 from the notch 462 and permit the cam disk and the cam 454 to turn.

Also secured to the rock shaft 472 is an arm 75

486 by which the rock shaft is actuated in a manner now to be described.

Referring to Fig. 4, a manually operable knob 488 is carried by a plunger 490 which is mounted 5 to slide horizontally in a guide hole in the machine housing 20. Pivoted at 492 to the plunger 490 is a controller bar 494 to the central portion of which is attached a pull spring 496 tending at all times to draw the controller bar toward 10 the left. A shoulder 498 (see Fig. 10) on the controller bar is arranged to engage a block 500 secured to the end portion of a member 502 pivotally mounted at 504 upon a swinging arm 506 which, in turn, is pivoted at 508 to an arm 510 15 secured to a vertical rock shaft 512 journaled in the table 22. A pull spring 514, attached at one end to the arm 506 and at the other end to a hook 516 screwed into the machine frame, tends to draw the arm 506 and the rocker arm 20 510 toward the left to a limit adjustably determined by a stop screw 518. A compression spring 520 between the member 502 and the arm 506 tends to keep those parts in the relation 25 shown in Fig. 10, the arm 506 having a pin 522 which passes slidably through a guide slot 524 in the member 502.

Pivotedly mounted at 526 upon the arm 506 is a dog 528 which is urged to turn in a counter-clockwise direction by a spring pressed plunger 30 530 but may be held against the action of said plunger by a locking pawl 532 held in a notch in the dog by a spring pressed plunger 534 and having a tail portion 536 which bears against a flat surface 538 upon the member 502. The 35 arm 506 and the member 502 carried thereby are drawn rearward around the pivot 508 by a pull spring 540 which is attached to the controller box at 542.

Projecting from the right hand end of the arm 40 506 is a slide 544 which is backed up by a spring 546 in such a manner as to permit the slide to yield toward the left a short distance into the end of the arm. The slide 544 is shouldered at 45 548, the shoulder being arranged to engage a block 550 secured to the clutch shifting lever 450.

The dog 528 is arranged at the same level as the cam 454 and swings into position to be engaged by the said cam when the locking pawl 532 releases it. Extending upward from the dog 50 528 is a lug 552 which, at a certain stage in the operation of the mechanism, engages a finger 554 which is adjustably secured upon the face 556 of the controller box by a bolt 558. The function 55 of the finger 554 is to reset the dog 528 at the proper time, as will be described hereinafter.

The upper end of the shaft 400 is diametrically slotted at 558 to receive a tongue 560 (see Figs. 2 and 8) formed upon the lower end of a shaft 562 to the upper end of which is secured 60 a drum 564. A strap 566 is wound around the drum, having one of its ends connected to the drum by a bolt 568 and its other end connected to the cutter head carrier at 570. A relatively light torsion spring 572 surrounding the shaft 65 562 maintains sufficient tension upon the strap 566 to keep the cutter head biased to a position in which an abutment 574 upon the cutter head engages a stop plug 576 mounted in the swinging cutter head arm 92 except when the cutters 70 are operating upon the work.

Extending downward from the gear 278 is an enlarged jack base 578 which is generally elliptical in shape. A vertical surface 580 is formed 75 upon the jack base parallel to the pitch line of

the internal rack 269 and spaced outward somewhat therefrom.

The surface 580 bears against, and is guided in its movement by, a guide bar 582 which is bolted upon the table 22 and the space between the guiding face of the bar 582 and the pitch line of the jack driving gear 268 is substantially the same as the distance between the pitch line of the internal gear 269 and the surface 580, so that as the gear 268 rotates the surface 580 is always held 10 in engagement with the face of the guide bar 582.

Secured to the under side of the jack base 578 are parallel grooved guides 584 which are arranged to slide upon tongues projecting from the side edges of a horizontal guide plate 586 upon 15 the upper end of an easily rotatable sleeve 588 journaled in the table 22 to turn about a vertical axis which is offset somewhat from the axis of the jack-driving gear shaft 266 which passes through the sleeve.

As a result of the construction just described 20 the jack is able to move in a straight line parallel to the guide bar 582 and to swing in semi-circles to which the guide bar is tangent. This manner of rotating the jack and the resulting movement 25 of the jack are substantially the same as in the machine of my previous application.

As the jack base 578 moves toward the right or left along the guide bar 582 the clamp frame 286, 287 must necessarily move with it and, in order to 30 keep this frame under proper control there is bolted to its base portion a downwardly extending arm 590 (Figs. 1 and 4) which has at its lower end a horizontal circular plate 592 guided for 35 straight-line movement parallel to the guide bar 582 and held down by gibbs 594 bolted to the table 22. It will be noted that the plate 364 which overlies the hook 362 has its edge extended in a line parallel to the gibbs 594 and is consequently 40 adapted to engage the hook at any point in the sliding movement of the clamp frame by which the hook is carried. It will be seen also that, by reason of the geared connection between the jack table 276 and the clamping posts 318, 320, the 45 clamp is constrained to turn with the jack table and remain in register therewith regardless of the 45 sliding and turning movements imparted to the jack.

Secured to the side of the jack base is a block 596 the function of which is to stop the jack automatically when it has made a complete revolution. One end of this block is arranged to engage 50 a dog 598 mounted at the upper end of the rock shaft 512 and arranged to be angularly adjusted about the axis of the shaft by means of two screws 55 600, 602 threaded through the dog and bearing against opposite sides of a pin 604 mounted in a disk secured to the shaft by a taper pin 698. It will be apparent from Fig. 10 that when the block 596 strikes the dog 598 the rock shaft will be 60 turned, moving the swinging arm 506 toward the right and actuating the clutch-shifting lever 450 to disengage the clutch 250 through which the jack is driven.

In the operation of the machine the motor 24 65 runs continuously, keeping the cutters 126 and 128 rotating at high speed and, through the planetary gearing 66, 68 and the connecting rod 76, causing the rack 80 to reciprocate and the disk 398 in the control unit to oscillate. Although 70 the disk 412 is held down and the one-way clutch 408, 414 is in condition for engagement, nothing occurs because the vertical shaft 400 is locked by the pawl 464 in position to hold the cutter head back against the stop 576 with the spring 222 com- 75

pressed, the extent of movement of the pawl 408 being no more than sufficient to take up the lost motion between it and the tooth 414 when the shaft 400 is locked in this position. Inasmuch as 5 the clutch shifting lever 428 is down, the jack driving clutch 250 is disengaged and the brake is set so that the jack is held stationary, the block 596 upon the jack base being in engagement with the dog 598, as shown in Fig. 10.

10 The operator depresses the treadle 350, raising the sole clamping members 318, 320, and places a sole blank 240 upon the pattern 272 beneath them. The treadle is then released, permitting the spring 306 to depress the clamp to hold the 15 sole blank securely upon the upper face of the pattern. Everything is now in readiness for the operation upon the sole blank to begin.

The operator now pushes upon the knob 488 which, however, cannot be moved inward until the 20 recess 484 in the periphery of the oscillating disk 398 reaches the position shown in Fig. 10. When this occurs the roll 432 can enter the recess and the member 502 is permitted to swing about the pivot 504 at the same time that the locking pawl 25 464 is retracted from the notch 462 to release the disk 420. When the disk 420 is released the strap 566 is permitted to unwind from the drum 564 at the upper end of the shaft 562 under the force exerted by the spring 422, tending to swing the 30 cutter arm 92 toward the jack.

Inasmuch as the torsion spring 572 is light 35 relatively to the spring 222 it merely keeps the strap 566 under sufficient tension to hold the abutment 574 against the stop plug 567 and thus 40 keep the cutter head so biased that as it swings toward the sole blank the cutter 126 will engage and operate upon the blank before the cutter 128. The result of this is that the rounding cutter 144 first cuts into the edge of the sole blank to the 45 full depth permitted by the gage 161 and the continued swinging movement of the cutter arm 92 then tilts the cutter head around the axis of the shaft 118 to bring the cutter 128 into operative engagement with the work. All of this occurs before the jack starts to move.

During the rotation of the shaft 400, which permits the cutters to be swung into engagement with the work, the cam 454 engages the dog 528, which has become unlocked when the swinging 50 of the member 502 turned the locking pawl 532 and has been swung by the plunger 530 into position to be engaged by the cam, and swings the arm 506 about the pivot 508 sufficiently to disengage the shoulder 548 from the block 550 and 55 permit the spring 546 to project the slide 554 a short distance toward the right beneath the block 550. This unlocks the clutch shifting lever 450. Now, when the striker 437 reaches the pawl 434 and disengages it from the lever 420 the arm 432 60 is thrown toward the left by the spring 433, raising the disk 412 and, through the rod 438, causing the lever 450 to be shifted about the pivot 452 in the direction to engage the clutch 250 with the rotating pulley 244.

65 Engagement of the clutch 250 results in the application of power to the jack, causing it to slide and turn through one complete revolution to traverse the entire periphery of the pattern 272, with the sole clamped upon it, past the 70 cutters. The movement of the jack is in a counterclockwise direction, as viewed in plan, and at the beginning of such movement the block 596 swings out of engagement with the disk 598 (see Fig. 10) permitting the spring 514 to draw the 75 arm 510 back against the stop screw 518. This

brings the shoulder 548 to the left of the block 550 with which the slide 554 is immediately re-engaged by the spring 540, ready to disengage the clutch 250 and stop the jack when it has made a complete revolution, at which time the block 596 again engages the dog 598 moving the arm 506 toward the right.

At the conclusion of the revolution of the jack as above described, the movement of the clutch shifting lever 450 draws the rod 438 toward the 10 right and, through the lever arms 432 and 428, lowers the disk 412 to a position where it is immediately locked by the pawl 434. Now, after the jack has stopped, the pawl 408 in the rotating disk 398 picks up the tooth 414 upon the disk 412 and causes the shaft 400 to be rotated 15 positively in a counterclockwise direction to rewind the strap 566 and thus to retract the cutters to inoperative position.

The movement of the arm 506 toward the stop 20 screw 518 when the block 596 left the dog 598 caused the lug 552 to engage the end of the finger 554 and reset the dog 528 so that when the jack has again stopped and the cutters have been retracted to inoperative position the control 25 mechanism has all been reset to the condition shown in Fig. 10, ready for the operation of the machine upon the next sole blank.

It will be seen that the position of the jack when it is at rest is such that the toe end of 30 the sole is pointing toward the left and the sole is in such a position that when the cutter 144 is swung toward it the cutter will engage the sole at the right hand side of the heel portion thereof. As indicated by the arrow in Fig. 6, 35 the cutter rotates in a direction to cause it to cut toward the rear end of the sole. The direction of rotation of the jack is opposite to this cutting action and the drag of the cutter as it enters the sole blank and starts to cut around the 40 heel end thereof is somewhat away from the heel clamping member 320 rather than toward said member, thus minimizing any tendency to cause the sole to buckle. This is especially desirable in the case of a block sole blank in which 45 there is an excessive amount of material to be removed around the heel portion.

Having described the invention, what is claimed as new and desired to be secured by Letters Patent of the United States is:

1. In a machine for operating upon soles, a 50 jack mounted for sliding and rotative movement through a complete revolution to traverse the entire periphery of a sole supported by the jack past an operating point, a rotary cutter mounted to swing toward and away from said operating point, means for continuously rotating the cutter, means for rotating the jack, and means for swinging the rotating cutter to the operating point and holding it in engagement with the sole throughout a complete revolution thereof.

2. In a machine for operating upon soles, a 55 jack mounted for sliding and rotative movement, means for turning the jack through a complete revolution, a rotary cutter mounted to swing from an inoperative position to an operative position in engagement with a sole upon the jack, means for continuously rotating the cutter, means operative while the jack is stationary to swing the rotating cutter into engagement with the sole, and means for thereafter causing said 60 turning of the jack through a complete revolution while the cutter is in engagement with the sole.

3. In a machine for operating upon soles, a 65

5 cutter, a jack mounted for sliding and rotative movement through a complete revolution to traverse the entire periphery of a sole supported by the jack past the cutter, means on the jack for supporting a sole pattern, a rotatable clamping member for holding a sole against the pattern, a support outside of the jack for said clamping member, and means carried by the support for maintaining the clamping member in register 10 with the sole pattern when the jack is rotated.

10 4. In a machine for operating upon soles, a rotatable jack, means on the jack for supporting a sole pattern, a movable, rotatable clamping member for holding a sole against the pattern, a bodily movable support for sustaining the clamping member which support is outside of, and movable relatively to, the jack, and means operating through said support to maintain the clamping member in register with the sole pattern when the jack is rotated.

15 5. In a machine for operating upon soles, a jack mounted for sliding and rotative movement, means on the jack for supporting a sole pattern, a rotatable clamping member for holding a sole against the pattern, a slidable support outside of the jack in which the rotatable clamping member is mounted, and means carried by said support for maintaining the clamping member in register with the sole pattern regardless of the 20 position of the jack.

25 6. In a machine for operating upon soles, a rotatable jack, means on the jack for supporting a sole pattern, a rotatable clamping member for holding a sole against the pattern, a slidable clamping member support having a base within which the jack rotates, connections between the jack and the clamping member for preserving a fixed angular relation between them when the jack is rotated, and means for simultaneously 30 imparting sliding movement to the clamping member support and causing rotation of the jack therein.

35 7. In a machine for operating upon soles, a movable sole clamp support having an elongated base, a jack mounted for rotation in one end of said base, the other end of said base being guided for sliding movement, means on the jack for supporting a sole pattern, a rotatable clamping member sustained by said clamp support in 40 register with the pattern, and means for imparting to the jack rotative movement relative to the clamp support base and sliding movement in the direction of the sliding movement of said base.

45 8. In a machine of the character described, a 50 slidable jack, a correspondingly slidable clamp for clamping work upon the jack, a treadle operated actuator for retracting the clamp, and a slidable connection between the actuator and the clamp, whereby the clamp may be operated in 55 any position.

55 9. In a machine of the character described, a 60 work supporting jack, a spring actuated clamping member for clamping work upon the jack, manu-

ally operable means for retracting the clamping member from the jack, and selectively shiftable means between said manually operable means and the clamping means for causing a given movement of the manually operable means to produce more or less retraction of the clamping means. 5

10 10. In a machine for operating upon soles, a sole pattern, a cutter arm mounted to swing toward and away from the sole pattern, a tilting cutter head carried by said arm, two cutters carried by said head, and means for so biasing the cutter head that the cutters will successively engage a sole upon the pattern when the cutter arm is swung toward the pattern. 10

15 11. In a machine for operating upon soles, a sole supporting jack, a cutter arm mounted to swing toward and away from a sole upon the jack, yielding means tending to swing the arm toward the sole, a tilting cutter head carried by the arm, two cutters arranged side by side upon 20 said head, and tension means acting in opposition to said yielding means so to bias the cutter head that the cutters will successively engage the sole when the arm is swung toward the sole. 15

25 12. In a machine for operating upon soles, a sole supporting jack, a cutter arm mounted to swing toward and from a sole upon the jack, spring means tending to swing the arm toward the sole, a tilting cutter head carried by the arm, tension means acting in opposition to said spring 30 means to bias the cutter head relatively to the sole, and means for exerting sufficient pull upon said tension means to withdraw the arm and cutters entirely from the sole. 25

35 13. In a machine for operating upon soles, a jack mounted for sliding and rotative movement, means on the jack for supporting a sole pattern, a swinging cutter carrier, a cutter on said carrier arranged to operate upon the edge of a sole held upon said pattern, means for holding the cutter 40 away from the pattern, mechanism for swinging the cutter to the edge of the pattern, mechanism for moving the jack to traverse the periphery of pattern past the cutter, and control mechanism constructed and arranged to prevent movement 45 of the jack before the cutter has been swung to the edge of the pattern. 35

50 14. In a machine for operating upon soles, a rotatable jack, means upon the jack for supporting a sole pattern, a clamping member for holding the heel portion of a sole against the pattern, a rotary cutter carried by a swinging support and adapted to cut into the edge of the sole at one side of the heel portion thereof, means for rotating the cutter in a direction to cause it to cut toward the rear end of the sole, 55 means for swinging the cutter into engagement with the sole while the jack is stationary, and means for thereafter rotating the jack in the direction opposite to its cutting action to cause the entire periphery of the heel end of the sole to be traversed past the cutter. 55

60 ERNEST W. STACEY.
